UNITED STATES PATENT OFFICE.

ARNOLD F. BRASZ, OF OSHKOSH, WISCONSIN, ASSIGNOR TO WAITE GRASS CARPET COMPANY, OF OSHKOSH, WISCONSIN, A CORPORATION OF WISCONSIN.

DESIGN FOR A GRASS RUG.

54,719.

Specification for Design.

Patented Mar. 23, 1920.

Application filed November 1, 1919. Serial No. 335,190. Term of patent 7 years.

To all whom it may concern:

Be it known that I, ARNOLD F. BRASZ, a citizen of the United States, residing at Oshkosh, in the county of Winnebago and State of Wisconsin, have invented a new, original, and ornamental Design for Grass Rugs, of which the following is a specification, reference being had to the accompanying drawing, forming part thereof, which shows a rug, in plan view, embodying my new design.

I claim:

The ornamental design for a grass rug, substantially as shown.

ARNOLD F. BRASZ.
